[57] ABSTRACT

A winding apparatus for forming a cylindrical package of a strand material comprises a stationary traverse assembly having a guide which reciprocates back and forth to guide the strand material onto the package, a mandrel that is movable relative to the traverse assembly for receiving a tube on which the package is wound, a drive train for driving both the traverse assembly and the mandrel by means of a single drive belt regardless of the relative positions of the traverse assembly and the mandrel, and a sensing device for sensing the diameter of the package and effecting movement of the mandrel in small increments away from the traverse assembly as the package builds.

APPARATUS FOR WINDING STRAND MATERIAL

BACKGROUND OF THE INVENTION

The present invention relates to an apparatus for winding a strand material and in particular to such an apparatus which is provided with a unique drive train and assembly for repositioning the mandrel relative to the traverse assembly. 5

The standard forming winders now being used, build a package which is tapered on each end to help prevent layers of yarn from sluffing off the ends. However, even with the use of tapered ends, the package size formed on these standard winders is limited when a diameter is reached wherein the succeeding layers of yarn start sluffing off the ends and make the package unfit for use. In addition, the inherent inaccuracies resulting from winding the yarn on these tapered packages causes yardage variations in the packages. 10

Many of these machines have traverse assemblies which recede from the mandrel as the package builds. As a result of the movement of the traverse assembly, the angle of introduction and departure of the strand relative to the strand guide changes thereby causing a change in the winding tension. As the strand is forced farther around the strand guide, the tension increases within the strand thereby causing the layers on the package to become more tightly wound as the package builds and increasing the probability of strand breakage. In addition, successive layers tend to overlap and become virtually tied together. Consequently the strands cannot be freely unwound from the package when the package is used in a subsequent process. 15

SUMMARY OF THE INVENTION

It is an object of the present invention to provide a winding apparatus which moves the mandrel away from the traverse assembly in such a manner as to maintain a constant tension on the strand and a unique drive assembly for the winding apparatus which is uncomplicated and permits the required movement of the mandrel relative to the traverse assembly. It is a further object to combine this type of assembly with a strand guide which is accurately reciprocated back and forth to develop a package which is cylindrical in shape with end walls that lie in planes substantially perpendicular to the axis of the package. 20

Accordingly, the present invention provides an apparatus for forming a cylindrical package of a strand material. The apparatus includes a traverse assembly, a mandrel assembly, a carriage assembly, a sensor assembly and a drive train. The traverse assembly is mounted on a frame of the apparatus in a fixed position and has a strand guide that is accurately reciprocated back and forth by a traverse drive to guide the strand onto the package. The mandrel assembly receives a tube on which the package is wound and is rotatably mounted on the carriage assembly which is movable relative to the traverse assembly. The sensor assembly senses a package diameter and effects movement of the carriage assembly in accordance with the sensed diameter to maintain the surface of the package in a substantially constant position relative to the strand guide. The drive train drives both the traverse drive and the mandrel. The drive train includes a drive belt trained about idler pulleys, a pulley of the traverse drive and a pulley of the mandrel in such a manner as to maintain a constant dis-

tance for the belt travel regardless of the distance between the pulleys of the traverse drive and the mandrel. 5

BRIEF DESCRIPTION OF THE DRAWINGS

FIG. 1 is a perspective view illustrating the general layout of the strand winding apparatus and its position relative to a bushing for producing strand material; 10

FIG. 2 is an end view of the apparatus substantially along lines 2-2 of FIG. 1 with portions removed to better illustrate the carriage, the drive train and the mandrel of the winding apparatus; 15

FIG. 3 is a side view of the drive train of the apparatus taken substantially along lines 3-3 of FIG. 1; 20

FIG. 4 is a plan view taken substantially along lines 4-4 of FIG. 1 with portions broken away to better illustrate the carriage, the drive train and the traverse assembly of the winding apparatus; 25

FIG. 5 is an end view of the traverse assembly and the mandrel to illustrate the relationship between a package on the mandrel and the traverse assembly; and 30

FIG. 6 is a view taken at the inner end of the traverse assembly to illustrate portions of the sensor assembly for initiating movement of the carriage. 35

DESCRIPTION OF THE PREFERRED EMBODIMENT

FIG. 1 illustrates a strand winding apparatus 20, a bottom portion of a bushing 22, a sizing applicator 24 and a gathering wheel 26. A number of glass filaments 28 are drawn from the bushing 22 and gathered into a strand 30 by means of the gathering wheel 26. The applicator 24 applies an appropriate sizing to the filaments before they are gathered into the strand 30. The strand 30 passes from the gathering wheel 26 to the strand winding apparatus 20 where it is wound into a package 32. 40

The strand winding apparatus 20 is provided with a traverse assembly 34 that guides the strand onto the package 32 which is carried on a mandrel assembly 36. The traverse assembly 34 includes a strand guide 38, a drive pulley 40, a traversing cam 42, a strand guide bar 44 and a strand starting guide 46. 45

The drive pulley 40 and the traversing cam 42 are affixed to a common shaft 48. The shaft 48 is rotatably supported by bearings (not shown) that are mounted in the traverse housing 50. These bearings support the shaft 48 intermediate the drive pulley 40 and the traverse cam 42 and at its outer end. With this construction when the drive pulley 40 is rotated the cam 42 is caused to rotate about the axis of shaft 48. 50

The cam 42 is provided with a pair of continuous spiral grooves 52 and 54 with transition grooves 56 at each end of the cam connecting the spiral grooves 52 and 54 together. The spiral groove 52 is a left hand helix and the spiral groove 54 is a right hand helix. These helices have the same pitch and consequently guide the strand guide 38 back and forth across the face of the package 32 at the same rate. The strand guide 38 is slidably mounted on a support bar 58 and is provided with a cam follower 60 which is received within and guided by the grooves 52 and 54 to accurately reciprocate the guide 38 back and forth across the face of the package 32. 55

The strand guide bar 44 is secured at its outer end to the traverse housing 50 and extends parallel to the axis of the mandrel assembly 36. The strand guide bar 44 is 60

located above the strand guide 38 between the strand guide 38 and the gathering wheel 26 to guide the strand 30 from the gathering wheel 26 to the strand guide 38.

The strand starting guide 46 is mounted on the outer end of the traverse housing 50 above the guide bar 44. The strand starting guide 46 is a piston type double acting air cylinder which is connected by pneumatic lines to a valve (not shown). By manipulating the valve the air cylinder can be actuated to extend or retract a piston rod which has an enlarged portion or guide 62 at its outer end. An outer surface of the guide 62 is aligned with a cylindrical starting surface 64 on the mandrel assembly 36. With this construction when the piston rod of the starting guide 46 is extended, the guide 62 diverts the strand 30 from its normal position which would be centered with respect to the traverse assembly 34 to the outer end of the traverse assembly where it is aligned with the starting surface 64 of the mandrel assembly 36. Upon retraction of the piston rod and consequently the guide head 62, the strand 30 moves back toward the center of the traverse assembly where it is automatically picked up by the strand guide 38 for the winding of the package 32.

The mandrel assembly 36 comprises the mandrel 66 which carries the package 32 and a shaft 68 on which the mandrel 66 is rotatably mounted. The mandrel assembly 36 is a motor with the mandrel 66 forming the rotor of the motor and the shaft 68 forming the stator of the motor. This motor is the sole driving means for both the mandrel assembly 36 and the traverse assembly 34. One end of the shaft or stator 68 is mounted in a clamping block 70 on a carriage assembly 72. The clamping block 70 supports the shaft and the mandrel is in turn, supported on the shaft or stator 68 by a bearing 74 near the clamping block 70 and a similar bearing not shown at the outer end of the shaft 68. The shaft or stator 68 is hollow and an electrical cable 76 for the motor pass from an electrical box 78 through the hollow shaft 68 to the windings of the motor.

The mandrel 66 includes a main portion which receives paper tubes for the packages 32 and an extension having a pulley 80 thereon. The pulley 80 is aligned with the drive pulley 40 of the traverse assembly. In this way, the mandrel motor not only effects the rotation of the mandrel 66 but also provides a drive for the traverse assembly 34.

The carriage 72 which supports the mandrel assembly 36 is slidably mounted on a pair of horizontally extending support rods 82 and 84 which are bolted or otherwise secured at their ends to the cabinet or frame of the assembly. The support rods 82 and 84 are parallel with respect to each other and extend perpendicular to the longitudinal axes of both the traverse assembly 34 and the mandrel assembly 36. The support rods 82 and 84 serve to both support and guide the carriage 72 in a direction which is perpendicular to the axes of the mandrel assembly 36 and the traverse assembly 34 so that the mandrel 66 with the package 32 thereon can be withdrawn from the traverse assembly 34 while being maintained in the correct orientation with respect to the traverse assembly 34 to assure the proper formation of the package 32.

The carriage 72 is also provided with a hydraulic double acting piston type cylinder assembly 86 for effecting the movement of the carriage along the support rods 82 and 84 both toward and away from the traverse

assembly 34. One end of the cylinder of the piston assembly 86 is secured by a bolt 88 to the cabinet while the other end of the housing is received within a recess 89 of the carriage 72. The outer end of the piston rod 90 of the cylinder is secured to the carriage 72 by a bolt 91. A four-way solenoid valve assembly (not shown) is provided to exhaust hydraulic fluid from one side of the piston to a reservoir while admitting pressurized hydraulic fluid to the other side of the piston from a pressure line to effect the movement of the piston and consequently the carriage 72. The valve is a three-position valve and is spring centered so that it normally is in its neutral position wherein both ports to the hydraulic cylinder 86 are closed. Upon actuation the valve is shifted from its neutral position to admit and exhaust hydraulic fluid from the cylinder 86 and thereby effect movement of the carriage.

In addition to the traverse drive pulley 40 and the mandrel pulley 78, the drive train of the winding apparatus includes an idler pulley 92 secured to the carriage 72 and an adjustable idler pulley 94 mounted on the frame of the assembly. The idler pulley 92 is rotatably mounted on a shaft 96 which is secured by means of a clamping block 98 to the carriage 72. The axis of rotation of the idler pulley 92 is parallel to the axes of rotation of the pulleys 40 and 80 and the pulley lies in the same vertical plane as pulleys 40 and 80.

The axis of rotation of the idler pulley 94 is also parallel to the axes of rotation of pulleys 40 and 80 and the pulley 94 lies in the same vertical plane as pulleys 40 and 80. The adjustable idler pulley 94 is rotatably mounted on a shaft 100 which is secured to a slide 102 by a pair of bolts 104. The slide is provided with a pair of depending blocks 106 which extend parallel to the axis of shaft 100 and are slidably mounted on a pair of rods 108 extending through the blocks and perpendicular to shaft 100 in a generally horizontal plane. The rods 108 which provide both support and guidance for the slide 102, are mounted in a pair of support blocks

110 and 112 that are affixed to the frame of the strand winding assembly. A shaft 114 is provided to effect movement of the slide 102 and consequently the idler pulley 94. One end of the shaft 114 is rotatably supported in a collar 120 which is mounted in block 110.

The collar 120 permits the shaft to rotate but prevents axial movement to the shaft 114 relative to the block 110. The other end of the shaft 114 is threaded and is received in threaded apertures within blocks 106. Consequently, by turning the shaft 114, the idler pulley 94 can be adjusted in a plane which includes the other pulleys of the drive assembly. In this manner the idler pulley 94 can be adjusted to provide the proper tension in a double sided toothed timing belt 116 which is trained about the pulleys. Once the pulley 94 has been promptly adjusted, a set screw 122 can be tightened to prevent further movement of the shaft 114.

The traverse drive pulley 40 and the idler pulley 94 are both mounted on the cabinet or frame of the assembly and remain stationary during the winding operation of the apparatus. The mandrel pulley 80 and the idler pulley 92 are both mounted on the carriage 72 and move with the carriage 72 as the mandrel 66 recedes from the traverse assembly 34 during the winding operation. The mandrel pulley 80 lies intermediate the traverse drive pulley 40 and the idler pulley 94. The line of travel of the belt from the traverse drive pulley 40 to the idler pulley 92 is parallel to the line of travel of

the belt between the mandrel pulley 80 and the idler pulley 94. As pulleys 80 and 92 move in a direction parallel to the line of belt travel between the pulley 40 and the idler pulley 92 plus pulley 80 and idler pulley 94, the change in distance of the belt travel between the pulley 40 and the idler pulley 92 is equal but opposite to the change in distance of the belt travel between the pulley 80 and the idler pulley 94. The result is that there is no net change in the distance of travel for the belt 116. Consequently, with this arrangement, the mandrel 66 which includes the pulley 80 can be moved toward or away from the traverse assembly 34 which is coaxial with the pulley 40 without the need for separate drives or drive trains for the traverse assembly 34 and the mandrel assembly 36. While the lines of travel for the belt intermediate the pulleys 40 and 92, plus pulleys 80 and 94 are horizontal, the movement of the carriage 72 is horizontal, and the pulley 80 is located in a vertical plane intermediate the pulleys 94 and 40 the drive assembly need not be restricted to this specific arrangement. As long as the direction of travel for the belt between the pulley 40 and the pulley 92 and between the pulley 80 and the pulley 94 are parallel, the movement of the carriage is parallel to this line of travel of the belt and the mandrel pulley 80 remains between the pulley 40 and the pulley 94. The drive assembly will function as desired.

A sensing unit 124 of the winding apparatus detects the diameter of the package 32 and actuates the four way valve for the hydraulic cylinder 86 to move the carriage 72 and consequently the mandrel 66 in accordance with the package diameter so that the mandrel 66 is properly positioned relative to the traverse assembly 34. The sensing unit 124 includes a roller bail 126 which extends the entire length of the package 32 and is supported by a pair of arms 128 which are affixed to a shaft 130. The roller bail 126 is a thin walled aluminum tube with a gas bearing mounted in each end that is in turn secured to one of the arms 128. The gas is supplied to the bearing from a source of pressurized air through bores in the shaft arms 128 and shaft 130. Since the roller bail 126 turns on gas (compressed air) bearings, there is no friction and very little inertia. Thus the roller bail 126 exerts little or no drag on the strand 30. The shaft 130 is rotatably mounted in the traverse assembly housing 50 and extends through the cabinet of the winding apparatus.

As shown in FIG. 6 the shaft 130 has a collar 132 affixed thereto which is provided with a radially extending arm 134. A spring 136 extends between and is secured to both the arm 134 and a bolt 138 in the frame of the apparatus. The spring 136 which is in tension exerts a clockwise torque (as viewed in FIG. 6) on the shaft 130 which in turn exerts a clockwise torque on the roller bail 126 to urge it into contact with the surface of the package 32. The force exerted is approximately 3 pounds which is distributed by the roller bail 126 across the entire surface of the package 32. This force is sufficient to keep the bail in contact with the package but the force is not high enough to damage the strand 30 as the strand is wound onto the package 32.

The collar 132 also includes a boss 140 which has a rod 142 mounted therein. The rod 142 extends upward from the boss 140 and has an upper end which is located adjacent a switch 144 which activates the valve for the hydraulic cylinder 86. The actuating arm 146 of

the switch 144 and the rod 142 are normally separated when the surface of the package 32 is in the correct position relative to the strand guide 38. However, as the package 32 builds in diameter the roller bail 126 is forced away from the mandrel 66 and rotates the shaft 130 in a counter clockwise direction thereby bringing the rod 142 into contact with the actuating arm 146 of the switch 144. In the preferred embodiment the switch is a touchswitch wherein contact between the rod 142, 10 which is a grounding rod, and the actuating arm 146 of the switch completes the circuit to actuate the valve for the hydraulic cylinder. When the rod 142 actuates the switch 144, the four-way valve for the hydraulic cylinder 86 is actuated to move the mandrel 66 away from 15 the traverse assembly 34 to thereby reposition the surface of the package 32 in the correct location relative to the strand guide 38. This allows the roller bail 126 to rotate in a clockwise direction under the influence of the spring 136 to bring rod 142 back to its original 20 position and deactivate the valve for the hydraulic cylinder.

Occasionally vibrations are set up in the mandrel 66 which could jolt or otherwise jar the roller bail 126 to cause a premature actuation of the hydraulic cylinder 86. To prevent this, a piston of a hydraulic shock absorber or dash pot 148 is connected to another arm 150 extending out from the collar 132 to dampen or eliminate any sudden movements of the roller bail 126. The hydraulic shock absorber 148 comprises a hydraulic cylinder 150 with inlet-outlet ports 152 and 154 on either side of the piston. The inlet-outlet ports 152 and 154 are connected by means of a fluid conduit 156 having a valve 158 therein to regulate the flow of fluid from one side of the piston to the other to thereby impede the movement of the piston and consequently, the rotation of the shaft 130 to prevent any sudden movement.

In operation, the strand 30 is first passed on the outside of the starting guide head 62, over the guide bar 44 and onto the surface 64 of the mandrel. As mentioned before, the starting surface 64 is beyond the paper tube on which the package is wound. As the mandrel 66 and the traverse assembly 34 are accelerating to their operating speeds the strand is wound on the starting surface 64 of the mandrel. When the mandrel 66 and the traverse assembly 34 have reached their operating speeds, a timed relay switch actuates the strand guide cylinder 46 to retract the starting guide. Once the strand guide 62 is no longer contacting the strand 30, the strand shifts toward the center of the traverse assembly 34 where it is picked up by the reciprocating strand guide 38. The strand guide 38 guides the strand back and forth across the paper tube and commences to build the package 32 on the paper tube. As the package builds, the roller bail 126 is pushed farther and farther away from the axis of the mandrel thereby causing the shaft 130 to rotate in a counterclockwise direction to bring the rod 142 into contact with the switch 144 that actuates the valve for the hydraulic cylinder 86. When contact is made with the switch 144 by the rod 142, the mandrel 66 is moved a small increment away from the traverse assembly 34 to again bring the surface of the package 32 into the proper position relative to the strand guide 38. With the movement of the package 32 away from the traverse assembly 34, the spring 136 again exerts a clockwise force about the shaft 130 to maintain the roller bail 126 in contact with the sur-

face of the package 32 and disengage rod 142 from the switch. This sequence of operation is repeated until a package of the desired diameter is formed.

With the unique drive assembly of the present invention the mandrel motor not only turns the mandrel 66 but also pulley 80 which in turn drives the belt 116. The belt 116 which is also trained over the pulley 40 as well as the idler pulleys 92 and 94 drives the traverse assembly 34 at a rate which is directly proportional to the speed of the mandrel 66. In addition, due to the unique placement of the idlers 92 and 94 and the relative position of the pulleys 80 and 40 relative to these idlers and each other, the mandrel 66 can be moved relative to the traverse assembly 34 without having to utilize separate drive trains for the mandrel 66 and the traverse assembly 34. The mandrel motor is provided with a conventional programmer which programs the motor to slow down as the diameter of the package 32 increases. This is done to provide a constant draw rate by maintaining a constant speed for the surface of the package 32.

The constant draw rate by the mandrel 66 together with the constant angle of introduction and departure of the strand 30 from the strand guide 38 and the constant angle of introduction of the strand 30 to the package 32 effected by movement of the mandrel 66 rather than the traverse assembly 34 permits a constant tension to be maintained on the strand 30. Since the traverse assembly 34 is driven by the mandrel 66 and since the speeds of these two elements are directly proportional, the traverse assembly 34 is slowed down as the mandrel 66 is slowed down which also contributes to the precision winding of the package 32. The strand is accurately guided onto the package 32 by the cam 42 and strand guides 38.

The roller bail is held in contact with the package 32, to assure proper actuation of the hydraulic cylinder 86 to move the mandrel, without exerting any drag on the strand 30. Consequently, the apparatus of the present invention forms an excellent package well suited for use in subsequent processes.

What is claimed is:

1. Winding apparatus for forming a package of a strand material comprising:
  - a. a frame,
  - b. a traverse assembly, said traverse assembly being mounted on said frame in a fixed position, said traverse assembly having a strand guide means for guiding a strand onto the package, and said traverse assembly having a traverse drive means for driving the guide means to reciprocate a strand in a direction generally parallel to a longitudinal axis of the package,
  - c. a mandrel for receiving a tube on which the package is wound, the mandrel being rotatably mounted on a carriage which is movable relative to said traverse assembly, means for moving said carriage to move the mandrel in a straight line away from said traverse assembly, the mandrel having a longitudinal axis generally parallel to the direction of reciprocation of the strand guide means, and

d. a motor for driving the traverse drive means and for rotating the mandrel, the motor having a rotor means integral with the mandrel and the the motor having a stator affixed to the carriage means for supporting the mandrel.

2. The winding apparatus of claim 1 wherein:

- a. the mandrel includes pulley means,
- b. the traverse drive means includes pulley means, and
- c. drive belt means drives the traverse drive pulley means off the mandrel pulley means, said drive belt means being trained over idler pulley means for permitting movement of said mandrel pulley means relative to said traverse drive pulley means without changing the net distance for belt travel about the drive train.

3. The winding apparatus of claim 2 wherein:

- a. the idler pulley means comprises a first idler pulley fixed relative to the mandrel pulley means and a second idler pulley fixed relative to the traverse drive pulley means, the first idler pulley being mounted on the carriage means relative to the traverse drive pulley means and the second idler pulley being mounted on the frame relative to the mandrel pulley means in such a manner that the change in distance between the first idler pulley and the traverse drive pulley means when said carriage means is moved is equal but opposite to the change in distance between the second idler pulley and the mandrel pulley means whereby the distance of belt travel about the drive train is unchanged.

4. The winding apparatus of claim 3 wherein:

- a. a line of travel of said belt between said first idler pulley and said traverse drive pulley means is parallel to a line of travel of the belt between said second idler pulley and the mandrel pulley means.

5. The winding apparatus of claim 1 including:

- a. sensing means for sensing the diameter of the package, and
- b. wherein said moving means for moving said mandrel comprises means for moving the carriage means in accordance with the sensed diameter of the package to move the mandrel relative to the traverse assembly to thereby keep a constant angle of introduction and departure between the strand and the strand guide and a constant angle of introduction between strand and the package.

6. The winding apparatus of claim 5 including:

- a. means for urging the sensing means into contact with the package and for keeping the sensing means in contact with the package, said means including a dash pot means to dampen any sudden movement of the sensing means.

7. The winding apparatus of claim 5 wherein:

- a. the sensing means includes a roller bail which is substantially equal in length to the length of the package and located to contact the entire length of the package and a means for urging the roller bail into contact with the package.
